Primary Examiner — Derrick Holland(74) *Attorney, Agent, or Firm* — Patterson + Sheridan, LLP(57) **CLAIM**

The ornamental design for a power activator, as shown and described.

DESCRIPTION

FIG. 1 is a top front perspective view of a power activator showing our new design;

FIG. 2 is a bottom rear perspective view thereof;

FIG. 3 is another top front perspective view thereof;

FIG. 4 is another bottom rear perspective view thereof;

FIG. 5 a front elevational view thereof;

FIG. 6 is a right side elevational view thereof;

FIG. 7 is a rear elevational view thereof;

FIG. 8 is a left side elevational view thereof;

FIG. 9 is another side elevational view thereof;

FIG. 10 is a top plan view thereof; and,

FIG. 11 is a bottom plan view thereof.

The broken lines shown represent the portions of the power activator that form no part of the claimed design.
